ANTENNA STRUCTURE

Herman Balton, Bloomfield, N. J., assignor to
Breeze Corporations, Inc., Newark, N. J., a corporation of New Jersey

Application May 17, 1946, Serial No. 670,357

6 Claims. (Cl. 250—33.65)

1

This invention relates to a directive antenna adapted to transmit or receive polarized radio waves. Such antennae are frequently of the mobile type and are provided with various means for retracting or storing them while they are being transported. The necessity of moving these antennae, chiefly by truck, has limited their practical size and consequently has restricted their range and effectiveness.

The broad object of this invention, therefore, is to provide a directional antenna equipped with extendable segments so as to increase its effective range.

Another object of this invention is to construct an antenna which may easily and quickly be reduced in a size so as to make it highly mobile.

A feature of this invention is the novel locking device at the ends of the extendable segments which enables the antenna to assume its desired parabolic shape.

Another feature of this invention is the construction of the extendable section frames whereby they become capable of being folded into a minimum of space or forming a rigid support when extended.

A further feature of this invention is the highly adjustable construction of the antenna mounting whereby it may be moved to any azimuth setting up to the full 360°, and raised to any desired angle of elevation.

A still further feature of the directional antenna is its mounting on the roof of the automobile truck whereby the folded antenna is brought to rest upon a plurality of resilient supports. This mounting assures the rapid raising or lowering of the antenna and its safe transportation.

Another object of this invention is the fully automatic nature of the antenna either in extending or retracting itself, once started.

This invention consists of the construction, combination and arrangement of parts, as herein illustrated, described and claimed.

In the accompanying drawings, forming part hereof, is illustrated one form of embodiment of the invention, in which drawings similar reference characters designate corresponding parts, and in which:

Figure 1 is a side elevation of a complete embodiment of the antenna.

Figure 2 is a rear view, in elevation of the antenna.

Figure 3 is a partial front view, in elevation, of the antenna reflector.

Figure 4 is a view, in perspective, of a segment frame.

2

Figure 5 is a view, in perspective, of a frame guide.

Figure 6 is a view, in elevation, showing the frame locking mechanism.

Figure 7 is a bottom plan view of the construction shown in Figure 6.

Figure 8 is a side elevation of a portion of the segment extending and retracting mechanism.

Figure 9 is a side elevation of the remainder of the construction shown in Figure 8.

Figure 10 is an enlarged view, in plan, of the frame hinge construction.

Figure 11 is a partial front elevation of the antenna, with the folded segments shown in dotted lines.

Figure 12 is a view in perspective of the antenna carriage assembly with certain parts omitted.

Referring to the drawings, and particularly Figure 1, 15 is the top of a mobile vehicle such as an automobile truck. A rotatable platform 16 is mounted upon the truck top 15 and is capable of being revolved through a full 360° by means of a motor 17 and a reducing gear 18.

A supporting carriage 19, clearly shown in Figures 2 and 12, is attached to the top of the turntable 16 and forms a base for the antenna supports 20, 21.

The antenna supports 20, 21 are substantially V shaped, as shown in Figure 2, and are attached at their upper extremities to bearings 22, 23.

Said bearings 22, 23 embrace the ends of a trunnion tube 24 upon which the antenna reflector is rotatably mounted. The trunnion tube 24 is rotated by an electric motor 25 and reducing gear unit 26 which are coupled to it by a shaft 27 and gearing 28.

The antenna support 20 which is closest to the parabolic reflector is pivoted at 29 upon the carriage 19. The rearwardly extending support 21 is freely mounted upon a cross-bar 30 which forms part of the carriage assembly. The upper ends of the support 21 are rotatably secured to the trunnion bearings 22, 23. The center of the cross-bar 30, best shown in Figure 12, is provided with pierced and internally threaded sleeve to form a nut 31. Said nut 31 is threaded upon a screw 32 which is supported against longitudinal movement by bearings on the carriage 19. Rotation of the screw 32, as by motor 33 or crank 33a, causes the nut 31 to travel upon the screw 32 in accordance with the direction of rotation.

The cross-bar 30 may thereby be moved forward along the inclined guideways 34 formed on the inner faces of the carriage frame 19. This forces the antenna support 21 forward and up-

ward, causing the inner support 20 to turn upon its pivot 29. The antenna is thus tilted through an arc of 90° until it comes to bear upon the rests 35 and 35a provided upon the truck roof 15, and assumes the position indicated in dotted lines in Figure 1. Said rests 35 are resilient and cooperate with rigid rests 35a to protect the antenna from damage during transportation. It is apparent that reversing the direction of rotation of the screw 33 will cause the antenna reflector to assume the erect position, shown in Figure 1.

The antenna reflector structure 36, best shown in Figures 2 and 3, radiates from a central hub 37 which is secured to the trunnion tube 24. A plurality of spokes 38 extend from the periphery of the hub 37 and secure a central rim 39 to the said hub 37. Attached to the rim 39 and radiating therefrom are a plurality of arms 40. Each arm is formed of two lengths of rigid tubing connected together at their outer ends and supported at intermediate points by braces 41. The arms 40 are bent to conform to the parabolic shape of the reflector and support a wire mesh 43 which is secured in place by metal strips 44 (see Figure 10). An outer rigid rim 42 holds the arms 40 in a fixed position. In the present embodiment of the invention this portion of the antenna has a maximum diameter of eight feet and comprises the rigid member herein-after referred to.

The remainder of the antenna consists of a plurality of folding sections which, when extended, increase the size of the antenna reflector 36 and the mechanical means whereby the unfolding and folding of the said sections is accomplished.

Each folding section 45 is made up of a rigid frame 46, shown in detail in Figure 4. Said frame 46 comprises two tubular side member 47 fastened at their inner ends to a tubular cross-member 48 and diverging toward their outer extremities where they are secured to an outer rim segment 49. The segment 49 is formed with an L shaped cross-section. The entire frame 45 is shaped so that the side members 47 conform with the parabolic shape of the reflector 36, the rim segments 49 are curved to the arc of the antenna perimeter, and the tubular cross-member 48 parallels the central rim 39.

Each frame 46 has a support 50 attached to the rear of one of the side members 47. Said support 50 gives the frame 46 rigidity while allowing the frames to be folded upon one another within a minimum of space. Braces 51 further strengthen this assembly.

The rim segment 49 is bent rearwardly at one end to form a guide member 52. A slot 53 is provided in the said guide member 52 and is shown in detail in Figure 5. A reinforcing bracket 54 is riveted to the guide member 52 and completes this construction. The opposite end of the rim segment 49 has a hook 55, shown in detail in Figure 6. The hook 55 engages with the slot 53 on the adjacent rim segment 49 when the antenna is extended. This joins the foldable sections 46 into a rigid structure. A guide roller 56 is positioned on the rim segment 49 so that it will ride along the rearwardly extended segment guide 52 and cause the hook 55 to catch the slot 53. A bottom plan of the hook and slot construction in engagement is shown in Figure 7.

The hook and slot construction cooperates to collapse the frames 46 when the antenna is be-

ing folded, since only alternate frames are provided with actuating linkage, as hereinafter described. Thus the motion of the actuated frames is transmitted through the hook and slot members to actuate all the frames.

The foldable frames are covered on one face with wire mesh 43 similar to that which was placed over the rigid member of the antenna reflector. The edge of the said mesh 43 is secured by thin metal strips 51 and 57a. These strips 51 also serve to maintain electrical contact between the several frames.

The mechanism by which the frames 46 are extended and folded is shown in Figures 8 and 9. Alternate arms 40 are provided with a push rod 58 which is attached to a nut 59 threaded upon a screw 60. The screw 60 is rotated by reduction gears, diagrammatically shown at 62, and is enclosed in a tubular housing 61. Said housing is freely pivoted at its end to allow for the motion of the push rod 58 when it is operated. The rotation of the screw 60 causes the nut 59 to move up or down its length. When the nut 59 is caused to travel forward it carries with it the push rod 58 which is coupled to a lever 63 at its other end. The lever 63 is pivoted at 64 upon the inner arm member and has fastened to its opposite end a link 65. Said link 65 is provided with a ball and socket joint 66 at each end and joins the pivoted lever 63 to the frame 46 of the folding section 45.

The folding section is hinged at each end of the frame to the rigid member of the antenna reflector. One end of the frame is rotatably supported by a bracket 67 which turns upon a pivot pin 68 carried by a bracket 69 mounted upon the rigid member of the antenna. The opposite end of the frame is pivoted upon a ball joint 70 carried by the rigid antenna member and entering a socket 72 at the end of an arm 71. The construction of the means whereby the foldable frames are hinged is best shown in Figure 10. It is clear that the exact positioning of the pivoted members is critical inasmuch as the arc through which each frame will travel in opening and closing depends upon this location. The major part of the weight of each frame is taken up by the pivot pin. Said pivot pin 68 lies in a different plane from the axis of the ball joint. The ball joint serves as a supplementary means of support and as a guide.

By referring again to Figure 9 it will be seen that as the link 65 is moved forward by the push rod 58 and lever 63, it forces the frame to rotate upon the pivotal members 68, 70 until it folds in upon the rigid portion of the reflector. As each alternate frame is swung inwardly it carries with it an adjacent frame, by the operation of the hook member 55, as herein previously described. The frames 45 finally come to rest, as shown in Figure 11, in an overlapping position wherein they occupy a minimum of space and may be easily stored upon the truck top 15.

A reverse motion of the push rod 58 will cause the frames to unfold and hook their peripheral segments 49 into a rigid outer rim. The antenna is thereupon ready for use. As the antenna becomes fully opened, a dog 73, shown in Figure 8, on the push rod 58 engages a roller 74 carried by the operating lever 75 of a limit switch 76, thereby stopping the actuating motor 77. A second dog 78 is attached to the push rod 58 for stopping the motor 77 when the frames are completely folded. This dog 78 operates a second limit switch (not shown) by engaging the lever 79.

thereof. The operation of the antenna is therefore fully automatic, once started.

An adjustable stop 80 is provided on the arm 40 to regulate the position of the frame 46 when the folding section is extended. This stop comprises a setscrew 81 which is threaded into a small flange 82 integral with the arm 40. A nut 80a locks the adjusted screw 81 in position. It is within the purview of this invention to adjust these stops 80 so as to focus the antenna upon a given point and thereby improve or intensify the transmitted signal.

The power necessary to actuate the folding members comes from a motor 77 mounted on the inner rim 39. As shown in Figure 3, this motor is connected to a train of hollow shafts 83 joined together by universal couplings 84, so that they may be placed around the circumference of the inner rim 39. The reduction gear 62 which turns the screw 60 in each of the activating arms is coupled to the shafts 83.

The focal point of the antenna reflector is occupied by the well known dipole 85 which is connected by co-axial cable 86 to the radio apparatus within the truck. Such apparatus may comprise a transmitter, a receiver or a combined transmitter-receiver, as used, for example, in radar.

Having thus fully described the invention, what is claimed as new and desired to be secured by Letters Patent of the United States, is:

1. In a parabolic directional antenna having a rigid parabolic central section adapted to support a plurality of foldable sections permanently affixed thereto, said sections comprising a frame of divergent side members, a cross member and an arcuate rim section, the whole being covered on one face by a wire mesh, means on said rim section to lock said sections together when extended and means for extending said foldable sections to form a rigid antenna structure.

2. In a parabolic directional antenna having a rigid parabolic central section adapted to support a plurality of foldable sections permanently affixed thereto, said sections comprising a frame of divergent side members, a cross member and an arcuate rim section, the whole being covered on one face by a wire mesh, means on adjacent rim sections comprising a slot on one rim engageable by a hook on the next rim to lock the foldable sections together when extended, and means for extending said foldable sections to form a rigid antenna structure.

3. In a parabolic directional antenna having a rigid parabolic central section adapted to support a plurality of foldable sections permanently affixed thereto, said sections comprising a frame of divergent side members, a cross member and an arcuate rim section, the whole being covered on one face by a wire mesh, means on adjacent rim sections comprising a slot on a rearwardly bent portion of one rim engageable by a hook on the next rim to lock the foldable sections together when extended, and means for extending said foldable sections to form a rigid antenna structure.

4. In a parabolic directional antenna having a rigid parabolic central section adapted to support a plurality of foldable sections permanently affixed thereto, said sections comprising a frame of divergent side members, a cross member and an arcuate rim section, the whole being covered on one face by a wire mesh, means on adjacent rim sections comprising a slot on a rearwardly bent portion of one rim engageable by a hook piloted by a guide roller on the next rim to lock the foldable sections together when extended, and means for extending said foldable sections to form a rigid antenna structure.

5. In a parabolic directional antenna having a rigid parabolic central section adapted to support a plurality of foldable sections, said foldable sections comprising a frame of divergent side members, a cross member and an arcuate rim section, the whole being covered on one face by a wire mesh, means on adjacent rim sections comprising a slot on one rim engageable by a hook on the next rim to lock the foldable sections together when extended, and means co-operating with alternate frames for extending said foldable sections to form a rigid antenna structure.

6. In a parabolic directional antenna having a rigid parabolic central section adapted to support a plurality of foldable sections, said foldable sections comprising a frame of divergent side members, a cross member and an arcuate rim section, the whole being covered on one face by an open work of conductive material, means on adjacent rim sections comprising a slot on one rim engageable by a hook on the next rim to lock the foldable sections together when extended, and means co-operating with alternate frames comprising in combination, a motor, a shaft attached to said motor, reducing gearing driven by said shaft, a screw actuated by said gearing, a nut riding upon said screw, a push rod attached to said nut, a lever actuated by the push rod, a link engaging said lever, for extending said foldable sections to form a rigid antenna structure.
